UNITED STATES PATENT OFFICE

HERBERT S. POLIN, OF SAN FRANCISCO, CALIFORNIA, ASSIGNOR, BY DIRECT AND MESNE ASSIGNMENTS, TO INTERNATIONAL RADIOPHONE CORPORATION, OF WASHINGTON, DISTRICT OF COLUMBIA, A CORPORATION OF DELAWARE

RADIO TELEPHONY

Application filed May 21, 1929. Serial No. 364,838.

My invention relates to automatic telephony.

More specifically, it relates to a system of automatic telephony, wherein radio communication is employed to connect the various subscribers of the system, for both the conversation itself and the calling or signalling.

My invention further comprises means whereby a dial of the appearance and mechanical actuation usual in automatic telephone systems is modified, so as to be electrically and mechanically suitable for use in such radio communication systems, to act as a calling or signalling device.

My invention further comprises automatic means for tuning the telephone apparatus of the calling subscriber to the wave length of the subscriber called.

Other objects and advantages of my invention will be apparent from the present specification in connection with the drawings attached thereto.

In said drawings:

Figure 1 is a diagram showing one type of circuit which may be used at the transmitting end of a subscriber's station.

Figure 2 is a diagram of a calling dial embodying variable condensers in its structure.

Figure 3 is a diagram showing, in front elevation, some of the mechanical and electrical elements of a dial.

Figure 3^a is a diagram of the same structure as Figure 3, but with the parts in a different position.

Figure 3^b is a section on line b—b of Figure 3, partly in elevation.

Figure 3^c is a diagram illustrating the operation of the contact arm shown at the right of Figure 3^b. This figure is a section on line c—c of Figure 3^b, looking in the direction of the arrows.

Figure 4 is a diagram showing an alternative circuit which may be employed as the transmitting means.

Figure 5 is a diagram of a circuit which may be used as the receiving means.

Figure 6 is a diagram of a portion of a circuit which may be employed to actuate

the signal or call at a subscriber's station, in response to the impulses transmitted from the calling subscriber's station, such as shown in Figures 1 and 4, for example. This circuit is connected to, and forms a part of, the circuit shown in Figure 5, and shows the connections relating to the relays V₁, V₂ and V₃ of Figure 5.

Referring now specifically to Figure 1, the transmitting portion of the subscriber's station comprises a thermionic tube 16, having a cathode 18 heated by any suitable means 21, a grid 19 and a plate 20. A telephone induction coil or its equivalent, comprising coils 63 and 59 wound upon core 62, is provided, the primary coil 63 being connected to the microphone 65 by means of conductors 64 and 67, a source of current 66 being interposed in conductor 67, as shown. One end of the secondary coil 59 is connected to the conductor 42, which is grounded at 60. The other end of coil 59 is connected to the grid 19 through a path including conductor 58, grid leak 55, conductor 56, coil 23 and conductor 24. Inasmuch as one part of the cathode 18 is also connected to the ground through conductors 61, 42 and 60, this provides a circuit whereby any speech currents originating in the microphone circuit will produce potential variations of the grid 19 with respect to the cathode 18. A by-pass condenser 22 is connected to one end of the coil 23 by means of conductor 56, and to the grounded part of the cathode 18 through conductor 57.

A dial 10, embodying in its structure a plurality of condensers 14, preferably ten in number to correspond to the ten digits of the arabic system of numbers, is connected into the circuit as follows:

Each condenser 14, here shown as a fixed condenser, has one terminal connected to the central shaft 118 of the dial, the other terminals being connected to the ten contact points 31 arranged upon the periphery of the dial, as shown. These contacts 31 are arranged so that any one of them may be connected, by appropriate means, hereinafter to be described, to the stationary contact 25, connected to conductor 26, as shown. Assuming that

at a given instant, the dial 10 is in the position shown in Figure 1, then at this instant the eighth contact 31 will complete the circuit through stationary contact 25, as follows:

- 5 From the grid 19, through conductor 24, to shaft 118, through said eighth condenser 14, contact 31, contact 25, conductor 26 and conductor 11 to the plate 20 of the tube 16. An oscillating circuit, comprising coil 23 in series with one of the condensers 14, is thus connected to the elements of the tube 16 in such way that oscillations will be set up thereby in the well known way, the frequency being determined by the inductance of coil 15 23 and the capacity of the condenser 14 at that time in circuit.

The energy producing these oscillations is derived from the source of current 36, here shown as a high voltage "B" battery, although 20 it will be understood that this showing is purely diagrammatic and any suitable source of power may be employed.

It will be further understood that, while, for convenience of illustration, various distinct sources of current are shown, in practice many or all of these may be combined so that all the power is derived from a single source, as is customary in radio circuits. This however, forms no essential part of the present invention, and many ways of accomplishing it are well known in the prior art. The negative terminal of the source of power 36 is connected to the cathode 18 by means of conductor 61, and the positive terminal leads 25 to the plate 20 through coil 32 and conductor 26, as shown. A by-pass condenser 35 connects the terminals of the power source 36 to each other through conductors 33, 34 and 61, as shown, and serves as a low-impedance 30 path for high frequency currents.

The coil 32 is coupled magnetically to coil 37, one end of which is connected to the grid 53 of a second thermionic tube 17, through the conductor 38, while the other end of this 45 coil is connected to the cathode 52 of the tube by means of conductor 39, "C" battery 40 and conductors 41, 42 and 50, in the order named. The cathode 52 of this tube is energized by a source of power 51 in a usual way. The output circuit of the second tube 17, comprises 50 a source of power 48 and a coil 45 connected in series between the plate 54 and the grounded conductor 42, by means of conductors 46, 47 and 49, as shown. The coil 45 is coupled 55 to a coil 43, which is located in the antenna circuit, comprising conductors 42 and 44 and the said coil 43.

A hook switch 28, controlled by the weight of a telephone receiver in the usual manner, 60 is provided to close an alternative circuit between the grid 19 and plate 20 of the tube 16, this circuit comprising part of conductor 24, variable condenser 30, conductor 29, switch arm 28, contact 27 and conductor 26. The 65 variable condenser 30 is mechanically con-

trolled by means operated by the dial, which will be more fully described hereinafter, and indicated diagrammatically by the dotted lines in Figure 1.

The purpose of this arrangement is to adjust the rotor of condenser 30 into a position corresponding to the last digit of the sum produced by adding the digits of the number which has just been called by the calling subscriber. The purpose of this arrangement 75 will be discussed fully hereinafter.

Three different types of dials are indicated respectively at 10, Figure 1; 12, Figure 2; and 13, Figure 4. The dial 10, as already mentioned, comprises a plurality of fixed condensers 14 embodied therein; the dial 12 is similar to the dial 10, except that the condensers 15 embodied therein are variable; and the dial 13 is the simplest of all, and comprises merely a single contact upon its 80 periphery, connected to the shaft 118 by means of conductor 113. The purpose of the dial, of whatever type it may be, is to control the frequency of the radio energy emitted by the calling subscriber's station 85 during the signaling period. The dials 10 and 12 accomplish this by virtue of the variation of capacity which is produced in the oscillating circuit upon the actuation of the dial, while dial 13, on the other hand, 90 controls a set of crystal oscillators directly governing the frequency of the radio currents produced.

Each of these dials, 10, 12 or 13, regardless of its electrical differences, is mechanically 100 substantially identical, and is illustrated in detail in Figures 3, 3^a, 3^b and 3^c.

Furthermore, each dial 10, 12 or 13 may control the impression of a low frequency ringing current on the emitted wave. This 105 is accomplished by the connections shown in Fig. 4, where the dial is arranged to control a switch 155, 157, to open the switch when the dial is at a normal position, and to close the switch to send the low frequency ringing current, when the dial is away from the normal position as described more in detail below.

Referring now specifically to said Figures 3, 3^a, 3^b, and 3^c, the dial mechanism there illustrated comprises a flat disc 335 having ten ratchet notches cut therein, as shown at 344, and also an additional notch with a curved bottom, 346. These notches cooperate with a pawl 313 carried by an arm 311 to which it is pivoted at 312. The arm 311 itself is pivoted at 310 to a stationary portion of the housing, 339, and is forced to the left by a spring 347 so that normally the pawl 313 is held against the periphery of the disc 335. The pawl 313 is urged downwardly by a spring 315 connected at one end to a pin 316 on the arm 311, and at its other end to the pin 314 on the pawl. A stop 317 secured to the edge of the disc 335 and movable 110

therewith cooperates with a fixed stop 318 secured to part 309 of the housing for example. This pair of stops serves to hold the disc 335 in its normally unactuated position.

5 A spiral spring 342 having one of its ends secured to the wall 309 and the other to the disc 335, tends to rotate said disc in a counter clockwise direction.

10 The operation of the structure so far described is as follows:

When the disc 335, which is provided with means, whereby the subscriber can actuate it with his finger, in the manner usual in automatic telephone dials, is drawn down 15 in correspondence with the first digit of the number being called, the pawl 313 will slip idly over the ratchet teeth 344 until the dial is released by the subscriber after the desired 20 digit has been reached. The pawl 313 is at that instant caught in the corresponding notch, and when the disc starts its return motion in response to the spiral spring 342, this pawl will be forced upwards and the bar 311 will therefore be caused to move to 25 the right, as shown in dotted lines in Figure 3^a until the pawl 313 is finally turned backwards, and then again slips freely over the remaining ratchet teeth of the disc 335. During the short period that the bar 311 is 30 pushed to the right, a connection is established between a contact 321, which is carried by a resilient element 322 secured to the bar 311 by means of a screw 323 and insulating material 324, and that one of the contacts 320, 35 carried by the disc 319, which corresponds to the digit in question. This connection is interrupted as soon as the pawl has been turned backwards, and while the disc 335 is returning to its normal position. When this 40 position is reached, the pawl 313 will again be turned into its normal "forward" position, because the curved notch 346 is deep enough to allow the spring 315 to return it to such position. Therefore, one ultimate result of 45 turning the disc 335 to any digit and then releasing it is to produce a momentary contact between element 321 and that particular contact 320 which corresponds to the digit in 50 question.

The disc 335 also carries a stud 154, which cooperates with a spring 155 carrying a contact 337, connected to wire 156, and cooperating with stationary contact 157 connected 55 to wire 160, in such fashion that when the disc 335 is in its normal position this stud 154 will abut against the end of the spring 155 and cause it to open the contact between 157 and 337, but, on the other hand, whenever the 60 disc is away from its normal position, this contact will be closed due to the spring 155. (See parts 154, 155 and 157 on Figure 4 also.) This contact is interposed in the signaling circuit and serves to complete said 65 circuit when, and only when, the dial is

being operated, as will be explained more in detail hereinafter.

The mechanism further includes another disc 331, having ratchet teeth entirely around its periphery, there being twenty such teeth, as shown. This disc 331 likewise has a spiral return spring 332 secured thereto at one end, and held upon a stationary stud 333 at its other end, as shown.

Two pawls, 327 and 328, cooperate with the teeth of this disc, and are held against the periphery of the disc by means of springs 329 and 330 respectively as shown. One of these pawls 328 is supported on a stationary pivot 326 secured to the casing wall 309; the other pawl 327 is carried on a pivot 325 secured to the disc 335. Upon a partial rotation of the disc 335, this last-named pawl 327 will engage in a notch of the disc 331 and carry it around a distance corresponding to 85 the number of tooth spaces said disc 335 is moved. Upon return of the disc 335 to normal position, the disc 331 will be prevented from also returning to normal, by the pawl 328. Upon each succeeding actuation of disc 90 335 the disc 331 will therefore be moved a corresponding number of teeth, and the final result will be that when the manual operation of disc 335 has been completed, the disc 331 will have been moved forward a 95 number of notches equal to the sum of the digits of the telephone number called. For example, should this be 678, the first actuation would move the disc 331 six teeth, the second one seven more teeth, and the final one eight more, or a total of twenty-one teeth in all. After each operation, the disc 335 returns to zero, but the disc 331 remains 100 set until finally released when the telephone conversation is terminated.

A contact bar 340 having two oppositely directed contact arms is connected to shaft 118, which carries the disc 331. This bar sweeps over a set of ten contacts 341 spaced 18° apart, as shown, that is, one-twentieth 105 of a circumference apart. Obviously, with this arrangement, one end of the bar 340 will engage the first of the series of ten immediately after the other end leaves the tenth, and thus during each revolution of shaft 118 110 each contact will be engaged twice in turn.

This feature is used to select the wave length of the talking current, which depends upon the sum of the digits of the telephone number called, ten wave lengths being thus available. These are designated by the last digit of said sum, for instance, in the case mentioned above, telephone number 678, the sum is 21 115 and the last digit of this sum is 1, hence wave length #1 is used here. As a further example, to make this clear, if the telephone number were 135, the sum would be 9, and therefore, this being the last (and only) digit, this particular call would be on wave 120 125 130

length #9. The pawls 327 and 328, when the disc 335 is in its normal position, will occupy the positions shown in Figure 3.

A bar 338, only the end of which is shown, 5 is connected mechanically to the receiver hook, so that when the receiver is replaced upon said hook the bar 338 will be depressed, thus pushing down the free ends of both pawls 327 and 328, and releasing the disc 331, 10 which thereupon returns to its normal position in response to the spring 332, and thus restores the entire mechanism to its normal position ready for a new call.

Referring now to Figure 4, there is illustrated another form of circuit embodying my invention. This circuit differs from that shown in Figure 1, in that it is far more sensitive, selective and powerful, these advantages being obtained by substituting crystal oscillators for the condensers in the dial of Figs. 1 and 2, and by substituting screened-grid tubes for the ordinary thermionic tubes used in the Figure 1 circuit.

In this form of embodiment the dial 13 is 25 simplified electrically to include merely a single contact element 113, the outer end of which is arranged to make contact with the stationary contacts 88 to 97 inclusive, arranged adjacent the circumference of the said 30 dial in much the same way as the contact 25 of Figure 1 cooperates with the dial contacts 31 of that figure. It will be understood, of course, that the stationary contacts are not all engaged by the dial contact 113 every time 35 said contact passes a stationary contact, but that the dial mechanism illustrated in Figs. 3, 3a, 3b and 3c will operate as in the other modification to cause a temporary connection with only that particular stationary contact 40 which corresponds to the highest digit to which the dial has been turned upon each actuation thereof.

It will also be understood that if the friction in the dial which retards its return to 45 the zero position should be insufficient, any of the usual known retarding means may be provided to slow down the return of the dial, in order to provide a sufficiently long time 50 of connection between the said rotating and stationary contact, in order that the wave filters hereinafter described may have sufficient time to conduct the corresponding wave length. A set of wave filters, such as 55 piezo crystals or the like, 68 to 77 inclusive are connected to the respective stationary contacts 88 to 97 inclusive, by means of conductors 78 to 87 inclusive, and the other terminals of said wave filters are connected by 60 wires 98 to 107 inclusive to the conductor 108, which is connected to earth by conductor 109, as shown. Another conductor 114 leads from the shaft 118 of the said dial to the grid 115 of a screen grid tube. A switch 65 comprising lever 155 and stationary contact

157 is placed into position to cooperate mechanically with the dial 13, as illustrated diagrammatically at 154. This is intended to show that by some mechanical connection between the shaft 118 and the element 154, the switch lever 155 will be removed from the stationary contact 157 whenever the dial is at normal position, but that the said switch 155—157 will be closed whenever the dial is 70 away from its normal position, for instance, in the position shown, wherein contact 88 is connected to the movable contact 113, and therefore to the grid 115 of the screen grid tube.

This switch 155, 157 controls the input 75 circuit of a low frequency ringer 161, which comprises a source of power 158, connected to the switch contact 157 by a conductor 160, and then through movable switch element 155 and conductor 156 to the ringer, and back to the source of power through conductor 159. The output side of this ringer is connected through conductors 162 and 163 to the primary coil 164 of a transformer comprising 80 also a core 165 and an output winding 166.

Referring back now to the screen-grid tube 85 which comprises grid 115, screen-grid 127, cathode 116 and plate 117, the grid 115 of this tube which is, as already stated, connected to the shaft 118 of the dial is also connected through conductor 121, coil 122, conductor 123, grid leak resistance 124 and conductor 125 to the common ground conductor 108. The cathode 116 of this tube is provided with a suitable energizing means 130, and is also connected through conductor 126 to the ground conductor 108. The screen-grid 127 is connected through conductor 128 to an intermediate potential point of a source 90 of power 153, which may be a "B" battery or a similar high voltage power source. A condenser 129 is interposed between the cathode 116 and the conductor 128, as shown.

The plate circuit of this tube comprises 95 a source of high voltage power 153, the negative terminal of which is connected to the ground conductor 108 by a conductor 152, the positive terminal of said power element 153 being connected through a coil 131 and conductor 132 to the plate 117. A circuit comprising conductor 120, condenser 118 and conductor 119 forms a shunt between the grid 115 and the plate 117, as illustrated. This screen-grid tube with its connected circuit, serves solely to amplify the oscillating 100 currents conducted by the wave filters 68 to 77 inclusive, and takes no part in the functions of signaling or talking.

A microphone 173 of any desired type is 105 connected through a conductor 172, source of power 171, conductor 170 and primary coil 169 of a transformer or induction coil, back to the microphone 173, as shown. The 110 said transformer or induction coil has a core 168 and output winding 167, as shown. This 115

output winding 167 is connected in series with the output winding 166 of the signaling transformer through a conductor 177 to the negative terminal of a source of energy 140, which furnishes a negative bias to the grid 135 of the second thermionic tube, shown in Figure 4, to which it is connected through the conductor 148, coil 138 and conductor 134, as shown.

10 The grid 135 is connected to the plate 117 of the preceding tube by means of conductor 132, condenser 133 and conductor 134, as shown. Thus, the coils 131 and 138 together with the stopping condenser 133 constitute what is known as an impedance coupling between the output circuit of the first screen-grid tube and the grid circuit of the second tube.

20 The screen grid 136 of this tube is connected by conductor 139, on the one hand, to an intermediate potential point of the high voltage power source 153 and, on the other hand, is connected through a stopping condenser 141 to the conductor 147, which connects the cathode 143 of the said tube to the ground conductor 108. The cathode 143 of this tube is energized by any suitable means 142. The plate 137 of the tube is connected to the positive terminal of the high voltage source 153 through conductor 146, coil 145 and conductor 144. The coil 145 is coupled inductively to the coil 110, one terminal of which is grounded through conductor 109, and the other of which is connected to the antenna 111.

25 A hook-switch 176 is illustrated diagrammatically and is so arranged that when the receiver is removed from the hook, the switch arm 176 will be connected with the stationary contact 175, which will close a path comprising winding 166, conductor 174, switch arm 176 and contact 175, so as to short circuit said winding 166 whenever the receiver is removed from the hook.

30 The operation of the circuit shown in Figure 4 is as follows: Upon actuation of the dial to call the remote subscriber, said dial will actuate the contact 113 to close one of the crystal circuits, when the said dial is released by the finger of the subscriber making the call. Thereupon the corresponding wave filter of the series 68 to 77, which are assumed to have different fundamental frequencies, will conduct oscillations which will be impressed upon the grid 115 of the first tube. This tube will amplify said oscillations very strongly, and in turn the amplified oscillations will be impressed upon the grid 135 of the second tube, through the interposed impedance coupling 131, 133 and 138. This tube in turn will amplify these oscillations and impress them upon the antenna 111 through the output coil 143, which is coupled to the antenna coil 110. During all this time, the low

frequency ringer 161 is producing low frequency impulses near or below the lower limit of audibility, which are impressed upon the input winding 164 of the transformer, whose output winding 166 is connected to the grid 135 of the second tube, thereby impressing oscillations of a ringing frequency upon said grid at the same time that the wave filters conduct their own high frequency oscillations to said grid.

35 Thus, high frequency oscillations modulated by the ringing frequency are impressed finally upon the antenna 111 and transmitted through space to the various receiving stations.

40 The low frequency ringer 161 will, of course, continue to be energized so long as the dial 13 is away from its normal position, and will automatically stop producing low frequency oscillations when the dial 13 re-opens the circuit by means of the switch 155-157. It will be further understood, that as soon as the calling subscriber lifts his receiver from the hook after completing the dialing operation, the corresponding hook switch indicated at 175, 176 will short circuit the output winding 166 of the ringing transformer, so as to remove its needless impedance from the talking circuit, until such time as the receiver is again returned to the hook and conditions are returned to readiness for signaling the next number to be called.

45 Referring now to Figures 5 and 6, there is indicated diagrammatically in these figures one arrangement which the receiving station may employ. The circuit comprises an antenna 182 connected to the ground through coil 181 and conductors 180 and 178, as shown. The energy received by the antenna is transmitted to the coil 183 by induction, and thence passes through conductor 184 to the grid 198 of the screen grid tube 221.

50 The other terminal of the coil 183 is connected to the negative terminal of a source of power 185, which furnishes a negative bias to the grid 198, and the other terminal of which is connected to the ground conductor 178, as shown. A by-pass condenser 191 is shunted across the terminals of said source 185 by means of the conductors 190 and 192, which connect it respectively to the conductors 193 and 178. The cathode 197 is provided with a suitable energizing means 196 and is connected to the ground conductor 178 through a conductor 179. The screen grid 199 is connected through a conductor 194 to an intermediate point of a high potential power source 219, the negative terminal of which is connected to the ground conductor 178 through conductor 220, and the positive terminal through the winding 202 of a transformer, and conductor 201, to the plate 200 of the said tube.

55 A by-pass condenser 195 is connected between the cathode 197 and the conductor 194.

leading to the screen grid 199, as shown. These elements constitute the input and output circuits of the screen-grid tube 221, the input side of which is tuned broadly by means of the coil 183 only, and this tuning may be made sharper by means of the condenser 186, which is connectible across the said coil 183 through conductors 187 and 190, and interposed hook switch 188, 189, which is so arranged that this switch will be closed when the receiver is lifted from the hook. Coil 183 and condenser 186 are tuned so as to have a receptive range sufficiently wide to pick up any wave length to which the circuits associated with coils 231, 241, 251 and 261 are tuned.

A second thermionic tube 222 is provided, and has a grid 206 connected through conductor 205, winding 204 and conductor 212 to the conductor 193 leading to the negative terminal of the source 185, as shown. A stopping condenser 214 may be connected between conductor 212 and conductor 213, as shown, and thence through conductor 178 to the cathode 210, which is suitably energized by a source of energy 211. The windings 202 and 204 may be arranged upon the core 203, as shown, although it will be understood that core 203 must be of a high frequency type, that is, the laminations must be of very thin good quality iron or steel, and if the frequencies are sufficiently high the core may be omitted entirely, thus constituting a transformer coupling between the plate 200 of the first tube 221 and the grid 206 of the second tube 222.

The output of the tube 222 comprises the winding 209, one terminal of which is connected through conductor 208 to the plate 207 of the said tube, and the other terminal of which is connected through the conductor 217 to the positive terminal of the source of high voltage energy 219.

Coupled to the winding 209 are a series of windings 231, 241, 251 and 261 respectively, each of which supplies the input energy for a corresponding one of a series of thermionic tubes 240, 250, 260 and 270. The first of these tubes 240 constitutes the amplifying means for the received talking currents, while the remaining three, 250, 260 and 270, are provided for signaling purposes only. Consequently a hook switch indicated at 227, 228 is provided and so arranged that when the receiver is lifted from the hook the circuit will be interrupted between stationary contact 227 and movable contact 228, whereby the energy from the power source 219 arriving through conductor 215 can not pass to conductor 229 when the receiver is off the hook, thus avoiding any needless flow of energy through the signaling tubes, except when they are actually used for signaling. These tubes and their connections will be described hereinafter.

Each coil 231, 241, 251 and 261, and their respective condensers 233, 243, 253 and 263 and associated thermionic tubes form different, individually pre-tuned circuits. The circuit associated with coil 231 is tuned to the talking wave length of this particular station and would be the same wave length as that selected by the dial 10, 12 or 13 at the end of the dialing operation. The circuits associated with coils 241, 251 and 261 would be tuned to different wave lengths, each the same as the wave length representing the calling wave lengths for this particular station, as determined by the dialing of the calling subscriber. That is to say, if the station represented in Figs. 5 and 6 is station number 357, for example, the respective circuits associated with coils 241, 251 and 261 will be tuned, respectively to the wave lengths sent from circuit established through contact points 3, 5 and 7 by the dial at the sending station.

The tube 240 which amplifies the conversation currents is connected to the output winding 231, which is connected to the cathode 237 through conductor 239 and to the grid 235 through the grid condenser 234, and grid leak 232, as shown, a tuning condenser 233 being connected in parallel with the coil 231. The cathode 237 of this tube is energized by suitable means 238. The receiver 224 is connected as usual in a circuit comprising the conductor 215, leading from the positive terminal of the source 219 and passing from the receiver 224 to the plate 236 through the conductor 225.

The signal operating tubes 250, 260 and 270 are coupled to the winding 209 in a manner similar to that of tube 240, each tube having a corresponding winding 241, 251 and 261, connected to its respective grid 245, 255, 265, through the grid condensers 244, 254 and 264, each grid condenser being shunted by a corresponding grid leak 242, 252, 262, and each winding 241, 251 and 261 being shunted by a tuning condenser 243, 253, 263 respectively, and being connected to the cathode 247, 257 and 267 through conductors 249, 259 and 269 respectively. Each cathode is actuated through a suitable source 248, 258 and 268. The plate 246 is connected to the positive terminal of the source 219 through a conductor 271, in which is interposed a vibration relay V_1 , thence through a conductor 229, through the hook switch 228, 227 and conductors 226 and 215 to the said positive terminal of source 219. Similarly the plate voltage is supplied to plates 256 and 266 through conductors 272, 273 and 274, 275, wherein are interposed the corresponding vibration relays V_2 and V_3 , respectively.

The vibration relays and their circuits are illustrated in Figure 6, although it will be understood that Figure 6 really forms a part

of Figure 5, and that the detailed circuits of V_1 , V_2 and V_3 are not shown in Figure 5 merely to avoid complicating the illustration. Connections 271, 272 and 273 appearing in Figs. 5 and 6 show the relationship between the two figures.

All three, V_1 , V_2 and V_3 are relays of the so-called "vibrating reed" or "resonance" type, wherein a contact is established only when current of the proper frequency is supplied thereto. Such relays are well known in the art and need no further description here, other than the statement that in general a reed is set into vibration by the field produced by an alternating or pulsating current in a coil, and this vibration becomes considerable only when the frequency of the current is near the natural frequency of vibration of the reed.

The relay V_1 controls a circuit comprising conductor 278, source of energy 279, conductor 280, electromagnet 281 and conductor 282, this circuit being connected to the contacts 276 and 277 of the relay, so that the electromagnet 281 becomes energized when these contacts are actuated. When the electromagnet 281 becomes energized it will attract its armature 285 and cause it to engage against contact 283. A dash pot 286 is provided to retard the return motion of the armature 285.

The relay V_2 is exactly like the relay V_1 and in turn controls a circuit comprising conductor 282, armature 285, contact 283, conductor 284, electromagnet 293, conductor 292, source of energy 291, and conductor 290, this circuit being connected to the contacts 288 and 289 controlled by the vibratory relay V_2 .

An armature 296 cooperates with the electromagnet 293 and is retarded by a dash pot 297, these parts being similar to the corresponding parts 285 and 286 of the first relay. When the electromagnet 293 is energized by current flowing from the source 291, and when the relay V_2 is closed and simultaneously relay armature 285 is in contact with 283, the armature 296 will be attracted by electromagnet 293, and thereby contact 294 will be connected with said armature, and will establish another circuit through conductor 295, electromagnet 303, conductor 301^a, source of energy 302, conductor 301 and the contacts 300 and 299 of the relay V_3 , thence through conductor 298 back to the armature 296. If, then, the contact 294 is connected to the armature 296 and simultaneously the relay V_3 be closed, the electromagnet 303 will be energized and in turn will attract its armature 305, connecting it with the contact 304, whereby the ringing circuit which is connected to the conductors 307, 308 will be closed and the signal of the called subscriber (not shown) will be actuated for a period depending upon the characteristics

of the dash pot 306, which retards the motion of the armature 305.

The operation of the circuits shown in Figures 5 and 6 is as follows:

When an impulse of radio frequency, within a certain range of wave lengths, strikes the antenna 182, the resulting currents produced in coil 183 will be amplified at radio frequency, first by the screen-grid tube 221, then by the three-element tube 222, which is transformer-coupled to the screen-grid tube, and then the impulse further amplified passes through the winding 209, which is coupled in turn to the four separate windings 231, 241, 251 and 261, connected to the respective tubes 240, 250, 260, 270. Each of these tubes as described has a detector circuit attached to the grid thereof, whereby the radio frequency impulses are converted into audio frequency impulses in the corresponding plate circuits.

As stated in the description of Figure 4, during the period that the dial is being operated, ringing currents of low frequency are superimposed upon the high frequency impulses emitted by the transmitting antenna, and these high frequency currents thus modulated are impressed simultaneously and successively on coils 241, 251 and 261, as determined by the dialing. The successive calling wave lengths are each different, and if they are such as the respective wave lengths to which the circuits associated with 241, 251 or 261 are tuned, and are sent in proper sequence, the bell will be rung at the station shown in Fig. 5. The final wave length impressed on this station is the wave length for this station, and is that to which 231, 233 and 240 are tuned. In the circuits of the tubes 250, 260, and 270, they will traverse the vibratory relays V_1 , V_2 , V_3 , and if the input circuit of any one of these tubes is tuned in resonance with the high frequency impulses received, the magnitude of the received current will be sufficient in that particular circuit to actuate the vibratory relay.

If the impulse be of such frequency that relay V_2 or V_3 is actuated without actuating V_1 , however, no signaling will result, for although the contacts of relay V_2 or V_3 might be closed, still they would not complete circuits which include the electromagnets 293 or 303, inasmuch as the circuit of the first relay is opened between 285 and 283. Therefore, it is essential that the relay V_1 be the first to operate, if the signaling means is to be actuated. This requires that the first impulse sent out must be of the frequency to which the tube 250 is tuned, in order that sufficient power may be fed to relay V_1 to bring its contacts together. When this condition has been established, the electromagnet 281 will be actuated, and this in turn will close the contact at 283, which will remain closed after the energization of 281 ceases for such period as the dash pot 286 is adjusted.

If, within this period, another impulse of a different frequency be received by the antenna 182, and in turn transferred to the various tubes, should the frequency of this impulse be that for which the circuit of tube 260 is tuned, the relay V_2 will be actuated, so that in turn it will cause the electromagnet 293 to be energized during the remainder of the period before the armature 285 breaks connection at 283.

Finally, if a third impulse be received by the antenna 182, and likewise this be of a frequency for which the circuit or tube 270 is tuned, the last electromagnet 303 will be energized in a similar way, and it in turn will close the ringing circuit and the bell of the subscriber being called will ring.

When he lifts up his receiver 224, he will automatically break the signaling circuit, and thus disconnect the three signaling tubes from the circuit, and likewise he will throw the condenser 186 across the input coil 183, thus sharpening the tuning very considerably and concentrating all the talking energy into the receiver circuit, namely, the circuit controlled by tube 240.

While for simplicity and convenience of illustration two different receiver hooks 189 and 228 have been shown, it will be understood that these are merely diagrammatic showings, and that both, in fact, are merely switches which are controlled by a single hook, namely, of one upon which the receiver 224 is supported when not in use.

It will also be obvious from the circuits shown, that unless impulses of the proper frequency are fed in proper sequence, and within predetermined limited times, to the three relays V_1 , V_2 and V_3 , no signal will be produced, although one or more or even all of the relays may be actuated in improper sequence.

These frequencies are, of course, determined by the dials 10, 12 or 13, as the case may be. It will also be understood that while only three relays of the types V_1 , V_2 , V_3 are illustrated, it is possible to use any desired number, dependent upon the number of digits in the largest telephone number to be called.

It is also obvious, of course, that if greater power be required at the transmitting end, or greater sensitivity at the receiving end, this may readily be provided by correspondingly increasing the number of thermionic tubes employed.

A further feature of the system employed in accordance with this invention is that the tube 240, over which the actual talking is done, has its input circuit tuned to a frequency corresponding to the last digit of the number obtained by adding all the digits of the called subscriber's own telephone number. For example, if his number were 153, the sum of the digits would be 9 and the last figure of this sum would therefore also be 9, or if

the telephone number were 678 the sum thereof would be 21 and the last digit of this sum would be 1.

It was stated previously in the description of Figure 1 that the variable condenser 30 is mechanically controlled by means operated by the dial.

The purpose of this condenser is to tune the transmitting circuit to the frequency corresponding to the last digit to which the dial 10 has been moved in that case, and this produces radio frequency currents of that frequency whenever the hook switch 28 has risen into contact with the stationary contact 27. Therefore, the calling subscriber automatically tunes his transmitting station to the frequency for which the receiving station he is calling has been adjusted. This is accomplished as is shown diagrammatically in Figure 1, and as shown more in detail in Figure 3c.

It must be understood, of course, that the various circuits and instrumentalities illustrated are purely diagrammatic in nature, and that in practice necessarily refinements and details will need to be considered which form no part of the invention itself, but are in accordance with ordinary telephone and radio practice.

It will also be understood that many deviations from the structures and circuits illustrated will occur in practice without departing from the spirit of the invention, which is defined by the following claims.

What I claim as my invention is:

1. A system of radio telephonic communication comprising a series of subscribers' stations, each having calling means including a manually operated dial capable of emitting a sequence of impulses of certain fixed wave lengths, and in an order determined by the movements of the dial, the movements of the dial also simultaneously establishing a frequency on which conversation can be carried on, and a receiving circuit which is responsive, at each station, only to a particular one of such sequences, whereby the signal of only that subscriber who is called will be operated.

2. A system of radio telephonic communication comprising a series of subscribers' stations, each having calling means including a manually operated dial capable of emitting a sequence of impulses of certain fixed wave lengths, and in an order determined by the movements of the dial, the movements of the dial also simultaneously establishing a frequency on which conversation can be carried on, and a receiving circuit which is responsive, at each station, only to a particular one of such sequences, whereby the signal of only that subscriber who is called will be operated, the receiving station being tuned to the same frequency as that established by the movements of the dial at the sending station.

3. A system of radio telephonic communication comprising a series of subscribers' stations, each having calling means including a manually operated dial capable of emitting a sequence of impulses of certain fixed wave lengths modulated by a low frequency wave length for ringing, and in an order determined by the movements of the dial, the movements of the dial also simultaneously establishing a frequency on which conversation can be carried on, and a receiving circuit which is responsive, at each station, only to a particular one of such sequences, whereby the signal of only that subscriber who is called will be operated.

4. A dial for use in radio telephony, comprising a plurality of contacts, and means cooperating with said dial, whereby upon partial rotation and return of said dial, only one of the contacts is caused to control a corresponding circuit, and other means cooperating with the dial, comprising a ratchet wheel, a pawl pivoted to the dial and engaging the teeth of said ratchet wheel, and a second pawl to prevent the ratchet wheel from returning when the dial returns to its normal position.

5. A dial for use in radio telephony, comprising a plurality of contacts, and means cooperating with said dial, whereby upon partial rotation and return of said dial, only one of the contacts is caused to control a corresponding circuit, and other means cooperating with the dial, comprising a ratchet wheel, a pawl pivoted to the dial and engaging the teeth of said ratchet wheel, and a second pawl to prevent the ratchet wheel from returning when the dial returns to its normal position, whereby the ratchet wheel is moved to an extent equal to the sum of the successive movements of the dial.

6. In a radio telephone having a transmitting circuit, a dial having a plurality of contacts, a receiver hook, a switch actuated thereby for controlling the transmitter circuit, and means cooperating with said dial, whereby upon partial rotation and return of said dial, only one of the contacts is caused to control a corresponding circuit, and other means cooperating with the dial, comprising a ratchet wheel, a pawl pivoted to the dial and engaging the teeth of said ratchet wheel, and a second pawl to prevent the ratchet wheel from returning when the dial returns to its normal position, and means connected to and actuated by the receiver hook for releasing both pawls when the receiver is returned to the hook, whereby the ratchet wheel will be capable of returning to its initial position.

7. In a radio telephone having a transmitting circuit, a dial having a plurality of contacts, a receiver hook, a switch actuated thereby for controlling the transmitter cir-

cuit and means cooperating with said dial, whereby upon partial rotation and return of said dial, only one of the contacts is caused to control a corresponding circuit, and other means cooperating with the dial, comprising a ratchet wheel, a pawl pivoted to the dial and engaging the teeth of said ratchet wheel, and a second pawl to prevent the ratchet wheel from returning when the dial returns to its normal position, and means connected to and actuated by the receiver hook for releasing both pawls when the receiver is returned to the hook, whereby the ratchet wheel will be capable of returning to its initial position, and a spring for returning the said ratchet wheel to its said initial position.

8. A dial for use in radio telephony, comprising a disc having a series of notches therein, constituting ratchet teeth, and a superposed ratchet wheel, a pawl cooperating with the disc to be actuated by one of the teeth thereof, contact controlling means actuated by said pawl, and a second pawl pivoted to the disc and cooperating with the ratchet wheel, and a third pawl also cooperating with the said ratchet wheel to retain it in the position to which it has been moved by the second pawl.

9. A dial for use in radio telephony, comprising a disc having a series of notches therein, constituting ratchet teeth, and a superposed ratchet wheel, a pawl cooperating with the disc to be actuated by one of the teeth thereof, contact controlling means actuated by said pawl, and a second pawl pivoted to the disc and cooperating with the ratchet wheel, and a third pawl also cooperating with the said ratchet wheel to retain it in the position to which it has been moved by the second pawl, and means for releasing said second and third pawls for engagement with the ratchet wheel.

10. A dial for use in radio telephony, comprising a disc, a ratchet wheel cooperating therewith, means whereby the disc shifts the ratchet wheel, a shaft connected to the ratchet wheel, a double armed contact lever operated by said shaft, and a series of stationary contacts cooperating with the said contact lever.

11. A dial for use in radio telephony, comprising a disc, a ratchet wheel cooperating therewith, means whereby the disc shifts the ratchet wheel, a shaft connected to the ratchet wheel, a double armed contact lever operated by said shaft, and a series of stationary contacts cooperating with the said contact lever, said contacts being so arranged that one end of the lever will always engage one of said contacts.

12. A system of radio telephone communication comprising a series of subscribers' stations, each station including manually controlled transmitting means for sending impulses of predetermined frequencies in a

given sequence at the will of the subscriber, and receiving means, the receiving means comprising a plurality of circuits tuned synchronously with the transmitted frequencies, 5 and further comprising a plurality of interlocking relays which are operated when waves of predetermined length are received in a predetermined sequence, the transmitting means being tunable, under the control 10 of the subscriber, so that it may be caused to correspond to the wave length of the station with which communication is to be established, said tuning being accomplished by the manual operation of the transmitting 15 means.

13. A system of radio telephonic communication comprising a series of subscribers' stations, each having calling means capable of emitting a sequence of impulses of certain 20 fixed wave lengths, and in an order determined by the calling subscriber, and a receiving circuit which is responsive, at each station, only to a particular one of such sequences, whereby the signal of only that subscriber who is 25 called will be operated, the receiver circuit being permanently tuned to one of a series of wave lengths, the designating ordinal of which is equal to the last digit of the number 30 representing the sum of the digits of the telephone number assigned to the receiving station.

14. A system of radio communication, comprising a series of subscribers' stations, each station including transmitting means, 35 and receiving means, the receiving means of each station being arranged to respond only to certain wave lengths sent in a particular sequence, the sending means of each station comprising means for sending in succession 40 a series of wave lengths in a particular sequence, the sending station further comprising means for sending as the final wave of the series, a talking or carrier wave of a wave length to which a certain receiving station, as determined by the sequence of successive waves sent by the sending station, is particularly tuned.

15. A system of radio communication, comprising a series of subscribers' stations, each 50 station including transmitting means and receiving means, the receiving means of each station being arranged to respond only to certain wave lengths sent in a particular sequence, the sending means of each station comprising means for sending in succession 55 a series of calling wave lengths in a particular sequence, for establishing communication with, and actuating a signal at, only the station of a particular subscriber, the sending station further comprising means for sending as the final wave of the series, a talking or carrier wave of a wave length to which a certain receiving station, as determined by the sequence of successive waves sent by the sending station, is particularly tuned.

16. A system of radio communication, comprising a series of subscribers' stations within operative range of one another, each station including transmitting means and receiving means, the receiving means of each station being arranged to respond only to certain wave lengths sent in a particular sequence, the sending means at each station comprising a plurality of sending circuits tuned to different wave lengths, and means, 70 selectively and manually operated, for controlling the operation of said sending circuits, for sending a series of waves having wave lengths, and in a sequence, as determined by the movements of said manually operated means.

17. A system of radio communication, comprising a series of subscribers' stations within operative range of one another, each station including transmitting means and receiving means, the receiving means of each station being arranged to cut in that station for operative communication only in response to a definite series of wave lengths sent in a definite sequence, the sending means at 90 each station comprising a plurality of sending circuits tuned to different wave lengths, and manually operated means for controlling said sending circuits, for sending a series of waves, having the desired wave 95 lengths, in the desired sequence.

18. A system of radio communication, comprising a series of subscribers' stations within operative range of one another, each station including transmitting means and receiving means, the receiving means of each station being arranged to cut in that station for operative communication only in response to a definite series of wave lengths sent in a definite sequence, the sending means at 100 each station comprising a plurality of sending circuits tuned to different wave lengths, and a manually controlled dial for controlling the sending circuits, for sending, in the desired sequence, a series of waves of 105 the desired wave lengths.

19. In a radio telephone, switch means for closing a plurality of circuits in succession, a tuning device in each of said circuits controlled by said switch means, a dial, selectively and manually operated and operatively connected with the switch means, for closing the several circuits controlled by said switch means in a sequence dependent upon the operation of the dial, and transmitting means cooperating with each of the tuning circuits, whereby a particular succession of radio waves is sent by said transmitting means, as determined by the movements of the dial and 120 its associated switch means.

20. In a radio telephone, switch means for closing a plurality of circuits in succession, a tuning device in each of said circuits controlled by said switch means, a dial, selec- 130

tively and manually operated and operative-
ly connected with the switch means, for clos-
ing the several circuits controlled by said
switch means in a sequence dependent upon
5 the operation of the dial, a circuit controlled
by said switch means and containing means
for producing a ringing signal, and trans-
mitting means cooperating with each of the

tuning circuits, and with the ringing signal
circuit, whereby a particular succession of
radio waves, followed by a ringing signal, is
sent by said transmitting means, as deter-
mined by the movements of the dial and its 70
associated switch means.

In testimony whereof I affix my signature.
HERBERT S. POLIN.
